UNITED STATES PATENT OFFICE.

HERMAN R. SAXON, OF TOLEDO, OHIO, ASSIGNOR, BY MESNE ASSIGNMENTS, TO
ELECTRIC AUTO-LITE CORPORATION, OF TOLEDO, OHIO, A CORPORATION OF
DELAWARE.

CONNECTOR.

1,426,323.

Specification of Letters Patent. Patented Aug. 15, 1922.

Application filed March 10, 1916. Serial No. 83,314.

To all whom it may concern:

Be it known that I, HERMAN R. SAXON, a citizen of the United States of America, residing at Toledo, Lucas County, Ohio, have invented new and useful Connectors, of which the following is a specification.

This invention relates to improvements in connectors, and particularly to improvements in connectors designed for use in a vehicle headlight.

The object of my invention is to provide an improved connector, which may be struck up from a single sheet of metal having a focusing arm struck out from the sheet.

Further objects, and objects relating to details of manufacture and economies in construction, will definitely appear from the detailed description to follow.

I accomplish the objects of my invention by the devices and means described in the following specification.

A structure constituting a preferred embodiment of my invention is illustrated in the accompanying drawings, forming a part 25 of this specification, in which—

Fig. 1 is a plan view of a sheet metal blank of stamped or cut contour for shaping into an electric connector tube or shell;

Fig. 2 is a side elevation of the insulated 30 terminal to be housed by the shell;

Fig. 3 is a perspective view of the blank of Fig. 1 at the first shaping operation after the contour forming;

Fig. 4 is a perspective view, of the blank 35 of Fig. 1 after the second forming or tube completing operation, and is in condition to receive the insulated terminal; and

Fig. 5 is a perspective view of the complete connector shell with the terminal anchored therein to provide a double ended 40 socket.

The blank 1 of sheet metal has the parallel ends 2 and 2', and the parallel longitudinal edges 3 and 4, as clearly shown in Fig. 45 1. The longitudinal edge 3 is cut away at 5 and 6 and the longitudinal edge 4 is cut away at 7 and 8 in such a fashion, that, when the shell is bent into its completed shape, the cut away portions 5 and 7 together form 50 a complete bayonet slot, and the cut away portions 6 and 8 also form a complete bayonet slot. Centrally of the end 2 of the blank, a bayonet slot 9 is stamped or cut out, and a similar bayonet slot 10 is cut out of the end 55 2' of the blank, and it will be apparent

that, when the tube is rolled into its completed shape, the bayonet slots 9 and 10 will be diametrically opposite the bayonet slots formed by the cut away portions in the edges 3 and 4 of the blank. Slots 11 60 and 12 respectively are cut in the end portions 2 of the blank midway between the edge 6 and the bayonet slot 9, and between the bayonet slot 9 and the edge 8. These two slots, 11 and 12, are T-shaped having 65 lateral extensions at their inner ends thereby forming the inwardly turned tongues 13, which engage the plug end of the lamp when it is inserted in the connector, to act as a vibration take-up and to hold it firmly 70 in place in the connection. The U-shaped slit 14' is formed in the body of the blank, as shown in Fig. 1, and a threaded opening 15 is provided in the space marked out or defined by said U slit.

The blank of sheet metal with its contour and the contour of the guides and projection all determined may, at a single operation, be struck up into the U form of Fig. 3 with the focusing arm 14 struck out at 80 approximately right angles and provided with a stiffening rib 16. This integral projection 14 serves readily to anchor the U form of the shell in position for completion of the tube by bringing the edge 3 adjacent the edge 4 as shown in Fig. 4. The connector shell is now complete and ready to receive the cylindrical insulation 17 carrying the spring plunger electric terminals 18. The terminals with their insulation housing 90 17 are inserted in the tubular shell and the parts so locked in assembled relation by pressing inwardly the shell at points 19 to hold the insulation 17 from longitudinal movement in the connector shell.

There is accordingly provided a connector shell of accurate form and registry as to all its coacting parts which shell may be made of cheap sheet metal for rapid and economic assembly.

I claim as my invention—

1. A connector comprising a cylindrical shell having a pair of bayonet slots in each end of the shell, a longitudinal slit connecting the bottom portions of one of each pair of said bayonet slots and a lug integral with said tube projecting outwardly at right angles thereto and spaced from said slit, said shell being adapted to receive a terminal supporting member and a lamp, and being 110

adapted to be moved longitudinally by said lug to focus the lamp.

2. A connector comprising a cylindrical sheet metal shell provided at each end with 5 diametrically opposite bayonet slots and having a longitudinal slit connecting a pair of said bayonet slots, said shell being pro- vided with an integral focusing arm punched out from the body of said shell at a point diametrically opposite said longitudinal slit and bent up at approximately right angles to said shell.

In witness whereof I affix my signature.

HERMAN R. SAXON.
